EX

DESIGN

J. ROGERS.
Statues.

No. 6,960.

Patented Oct. 14, 1873.

James M. Hart

C. B. Arnold

John Rogers

UNITED STATES PATENT OFFICE.

JOHN ROGERS, OF NEW YORK, N. Y.

DESIGN FOR STATUE.

Specification forming part of Design No. 6,960, dated October 14, 1873; application filed September 4, 1873.
[Term of Patent 14 years.]

To all whom it may concern:

Be it known that I, JOHN ROGERS, of the city, county, and State of New York, have invented and produced a new and original Design for a Piece of Statuary, of which the following is a specification:

The nature of my design is fully represented in the accompanying photographic illustration, to which reference is made.

The statue is called bubbles, and represents a boy scantily clothed, and with legs and arms bare. He is seated on the door-steps, his left

foot resting on the ground, and his right on the lowerstep. In his left hand he holds, against his side, a bowl of suds, from which he has blown a bubble, which he is trying to detach from the pipe which he is holding up in his right hand.

I claim as my invention—

The design for a statue, as shown.

JOHN ROGERS.

Witnesses:

JAMES M. HART,
C. B. ARNOLD.
